UNITED STATES PATENT OFFICE.

ARTHUR F. POOLE, OF WHEELING, WEST VIRGINIA.

ELECTRIC CLOCK.

SPECIFICATION forming part of Letters Patent No. 708,253, dated September 2, 1902.

Application filed September 7, 1901. Serial No. 74,653. (No model.)

To all whom it may concern:

Be it known that I, ARTHUR F. POOLE, of Wheeling, in the county of Ohio and State of West Virginia, have invented a new and useful Electric Clock, of which the following is a full, clear, and exact description, reference being had to the accompanying drawings, forming part of this specification, in which—

- 10 Figure 1 is a front elevation of a master-clock constructed in accordance with my invention, the parts being in their normal position. Fig. 2 is a similar view to Fig. 1 looking in the opposite direction and showing the parts in a different position. Fig. 3 is a front elevation of the synchronizer which I employ. Fig. 4 is a similar view showing the top plate removed, the parts being shown in full lines in the same position as that illustrated in Fig. 3 and in dotted lines showing the parts in the second position of the synchronizer, as illustrated in Fig. 2. Fig. 5 is a side elevation of the left-hand side of the synchronizer. Fig. 6 is a view similar to Fig. 4, showing the parts in the third position just previous to their return to the normal position shown in Figs. 1, 3, and 4. Fig. 7 shows a diagram of the electrical circuits of the master-clock and the secondary clocks, the parts being shown 20 in their normal position. Fig. 8 is a view similar to Fig. 7, showing the synchronizer-switches in full lines corresponding to Fig. 2 and the dotted position of Fig. 4 and in dotted lines to the third position, as shown in Fig. 6. Fig. 9 is a front elevation, on a larger scale, showing a preferred form of secondary clock. Fig. 10 is a side elevation of the same, and Fig. 11 is a detail sectional view showing the gearing of the center shaft.
- 30 My invention relates to the class of electric clocks wherein the master-clock through a series of electrical connections actuates the secondary clocks and is designed to provide means for sending out suitable impulses to the secondary clocks, so as to bring them into synchronization with the master-clock, and also to send out impulses which may be used for actuating the striking mechanism of the secondary clocks as well as to set them up.
- 40 Another object of my invention is to provide a master-clock which when it is synchronized from a primary clock will itself syn-

chronize the group of secondary clocks driven by it.

To that end my invention consists of a master-clock provided with means for sending out impulses, which I have shown in the present case to be at intervals of one minute, and mechanism for setting these parts again in their normal position, and a synchronizer controlled preferably by a cam rigidly secured to the minute-hand arbor of the clock, the synchronizer being provided with means for controlling the direction and intensity of the impulses sent out at predetermined periods.

My invention further consists in employing secondary clocks which are provided with polarized detents which control the advance of the hands and, further, in providing striking mechanism for said secondary clocks which is unaffected by the normal impulses sent out by the master-clock, but which is affected by the impulses of greater intensity. The impulses which operate the striking mechanism are a whole or a part of a series of impulses sent out in quick succession between two consecutive normal impulses, preferably just before the next succeeding hour, so that slow clocks are advanced the number of impulses sent out until brought into synchrony with the master-clock.

It also consists in the construction and arrangement of the parts as hereinafter more fully described, and set forth in the claims.

In the drawings, 2 represents an ordinary clock-train, which may be driven in any suitable manner and forms of driving mechanism of a master-clock.

3 is the seconds-hand arbor. Upon this arbor are frictionally mounted two cams 4 and 5, the latter being shown in dotted lines. These cams are rigidly connected together, so that the movement of the heart-shaped cam 5 will move the cam 4.

Mounted upon the frame of the master-clock is an angular lever 6, pivoted at 7 and having an arm 8 provided with a pin 9, adapted to be engaged by the cam 4 on the seconds-hand arbor 3. The other arm 10 of the lever 6 is preferably weighted, so as to hold the lever in the desired position for engagement with the cam 4. Projecting from the weighted arm 10 are stop-pins 11 and 12, which are so arranged as to engage in succession a pin 13 on

one arm of the bell-crank lever 14, pivoted at 15 to the frame of the clock. A weighted arm 16 tends to make the bell-crank lever 14 drop when the pin 13 is released from engagement 5 with either of the pins 11 or 12.

A short lever-arm 17 has a stud or pin 18, to which is secured a link 19, which is secured at its opposite end to a stud or pin 20 on the crank-arm 21, secured to a rock-shaft 22. This 10 rock-shaft is provided with a projecting arm 23, which is adapted to engage a corresponding arm 24 on a rock-shaft 25, to which is secured a detent 26. A slight space or gap is left between the arms 23 and 24, so that 15 when the pin 13 is released from the pin 11 and falls into engagement with the pin 12 the detent 26 is not released from its engagement of the segmental rack 27, mounted on the rock-shaft 28 of the repeating-switch 29. This 20 repeating-switch 29 is similar to that shown in my copending application, Serial No. 38,915, filed December 6, 1900.

Upon the rock-shaft 28 is mounted a liquid-switch 30, provided with terminals 31 and 32, 25 one of which is normally out of contact with the liquid in the tube, as shown in Figs. 1 and 7. On the opposite end of the rock-shaft 28 is mounted an armature 33, arranged to vibrate between the poles of the electromagnet 34, these electromagnets being in the same electrical circuit as the switch. When the detent 26 is released, the tube swings by gravity into a position more nearly horizontal under the influence of the weighted arm 35, and 30 the liquid then flows over both terminals and closes the circuit. The current then passes through the electromagnets 34 and acts upon the armature 33 and causes the same to return to its original position, when the circuit 35 is again broken, and so long as the detent 26 is held out of engagement with the segmental rack 27 the vibration of the repeating-switch will be continued and one impulse after another will be sent out under the normal operation 40 of the repeating-switch, as the detent 26 is operated by gravity and engages the toothed segment 27 and remains in this position until again tripped by the mechanism just described. The mechanism by which 45 the repeating-switch is set in motion is reset in normal position by means of an arm 36, mounted on a rock-shaft 37, to which is rigidly attached an armature 38, actuated by electromagnets 39, which are in the same circuit 50 as the repeating-switch 29, and the circuit through these magnets is closed by the liquid-switch 30. This closing of the circuit causes the armature to be moved by the magnets so that the arm 36 is raised, and a pin 40 55 on the arm 36 is brought into engagement with the arm 16 of the bell-crank lever 14, and thereby lifts the bell-crank so that the pin 13 is brought into the position to engage the pin 11 as soon as the circuit is broken and 60 the arm 36 has dropped away from the bell-crank 14. I will now describe the operation

of this part of my device used in sending out an impulse every minute.

As the seconds-hand arbor revolves the cam 4 is brought into contact with the pin 9 70 on the arm 8 of the lever 6 and by contact with the said pin 9 depresses the arm 8 and lifts the weighted arm 10 gradually, so that the pin 11 is lifted out of engagement with pin 13 on the bell-crank 14, and by reason of 75 the weight of the arm 16 of the bell-crank 14 the pin 13 is brought into engagement with the pin 12 on the arm 10 on the lever 6. This movement through the connection of the bell-crank 14, the arm 17, link 19, and crank-arm 21 on the rock-shaft 22 brings the arm 23 into contact with the arm 24, secured to the rock-shaft 25, which carries the detent 26 without tripping the same. As the seconds-hand arbor further revolves the arm 8 is released, and the pin 12 drops out of engagement 80 with the pin 13 on the bell-crank lever 14, which then falls by gravity until the weighted arm 16 engages the pin 40 on the lever 36, which rests on a suitable backing-pin, and this movement 85 of the bell-crank causes the arm 17 through the connecting-link 19 to lift the crank-arm 21 upon the rock-shaft 22, thereby causing the arm 23 to engage the arm 24 on the rock-shaft 25 in such a manner as to release the detent 26 from engagement with toothed segment 27 of the repeating-switch. The switch 90 upon being released swings by gravity, as previously described. The circuit is then closed in the liquid-switch 30 and energizes 10 the magnets of the repeating-switch and the magnets 39 of the restoring device. This energizing of the magnets causes the armature to move, so that the liquid-switch is again 105 brought into its normal position, and the arm 36, carrying the pin 40, is raised, and by means of this pin 40 the bell-crank lever is raised to its normal position, the lever 6 having been previously brought into this normal position 110 as the pin 9 left its engagement with the cam 4 and left it in the proper position to engage the pin 13, as shown. This movement of the bell-crank through the connections described 115 brings the detent 26 into proper position to engage the toothed segment, and thus retain 120 the repeating-switch in its normal tilted position.

On the minute-hand arbor of the clock-frame is frictionally mounted a sleeve, which carries a cam 41, having a high and low surface 42 and 43. Upon the sleeve carrying the cam 41 is a second cam 44, the function of which I will hereinafter describe. At a suitable point upon the frame of the clock a bent lever 45 is pivoted at 46 and has an arm 47, provided with a pin 48, adapted to engage the cam-surfaces 42 and 43 of the cam 41. The weighted arm 49 of this bent lever is provided with pins 50 and 51, adapted to engage pin 52 on the arm 53 of the bell-crank lever 54, which is pivoted at 55 of the frame of the clock. To the weighted arm 56 of the bell-

crank 54 a link 57 is connected at its upper end and at its lower end to a tripping-lever 58, by which the liquid-switches of the synchronizer are released. The synchronizer comprises a suitable frame having an outer plate 60, to which are secured a requisite number of binding-posts, and an inner plate 61, suitably spaced from the front plate 60 by post 62. Between these plates I mount the tripping mechanism and the resetting mechanism.

On a shaft 63 is mounted a double catch having arms 64 and 65, the arm 64 being adapted to engage an arm 66 on the shaft 67, upon which is mounted a two-way liquid-switch 68, having terminals *a*, *b*, and *c*, the shaft 67 being so counterweighted that when the arm 66 is released the tube will assume the position as shown in Fig. 8. The shaft 67 is also provided with a finger 69, which is adapted to engage with the pivoted dog 70, pivoted on the arm 71 at the point 72. This pivoted dog is normally held out of engagement with the finger 69 by a pin 73, secured to the plate 61. This pin also acts as a stop to limit the movement of the lever 71, the lever being secured to the shaft 74, which has secured thereto an armature 75, actuated by electromagnets 76 in one direction and by a retractile spring 77 in the opposite direction.

The shaft 63 is provided with an arm 63', which is adapted to be engaged by adjustable pin 58' on the lever 58. The shaft 63 is also provided with a pin 78, adapted to receive the tension-spring 79, which is connected at its other end to pin 80 on shaft 81. This shaft 81 has an arm 82, which engages an arm 83, which projects from the shaft 84, this shaft being provided with a finger 85, which is engaged by a pivoted dog 86, provided with a weighted arm 87 and a tail 88, which engages a stop 89, projecting from the rear of the front plate 60, as shown in Fig. 3. The dog 86 is carried upon an arm 90, which is rigidly secured to a shaft 91, which is provided with an armature 92, which is actuated by electromagnets 93 in one direction and by the spring 77 in the opposite direction. Upon the shaft 91 is secured an arm 94, to which is pivoted a gravity-pawl 95, which engages a ratchet-wheel 96, provided with seventy-eight teeth. The feeding action of the pawl is limited by a stop-pin 97, so that the wheel 96 is advanced one tooth at a time, a suitable device preventing any retrograde movement.

Upon the shaft 99, which carries the toothed wheel 96, is secured a disk 100, provided with notches 101, located at intervals in its periphery, the spaces between the notches being progressively greater from one to twelve, corresponding with the hours. Upon a shaft 102 is secured an arm 103, adapted to engage the pivoted dog 86 when the finger 104 is moved from the lowest point of the notch 65 outwardly upon the periphery of the disk 100.

Upon the shaft 84 is mounted a double-path liquid-switch 105, similar to the switch 68 and

having terminals *d*, *e*, and *f*. The shaft 84 is also provided with a counterweight 106, which tilts the tube downwardly when the 70 detent arm 83 is released. Its downward movement is limited by a suitable stop-pin, as is also the movement of the arm 82. The tripping-lever 58 is connected to the ratchet-feed mechanism by a link 59, provided at its 75 lower end with a slot 59', which moves on a pin 90', secured to an arm 94' upon the shaft 91, so that the train of mechanism by which the synchronizer is released by the master-clock is restored to its normal position on the 80 first stroke of the armature 92, actuated by the electromagnets 93.

I will now describe the electrical connections which I employ.

In the master-clock I use three circuits during three distinct periods of the hour. The one used during the first period of the hour to send out currents of normal intensity in one direction is that shown in Fig. 7. Starting at the plus pole of battery A the current 85 passes to binding-post 107, thence to the electrode *a* of the liquid-switch 68, through the liquid to the terminal *b* of said switch, thence to binding-post 108, to binding-post 109, then through the secondary-clock circuit, this circuit returning to the master-clock at binding-post 110, thence to binding-post 111, which is a terminal of one of the coils on one leg of the magnet 34, which actuates the repeating-switch 29. In this switch the current passes 90 to binding-post 112, thence to electrode 31 of the electric switch 30, which when the switch is in operation will close the circuit through the liquid-switch, as shown in dotted lines, the liquid connecting the terminal 31 and 95 the terminal 32. The current passes thence to binding-post 113, then to binding-post 114, from which it is carried to terminal *e* of the liquid-switch 105, thence through the conducting liquid to the terminal *d*, thence to the binding-post 116, then through the other coil 34 of the repeating-switch 29, thence to binding-post 117, then to binding-post 118, then passes through magnet 76, controlling the switch 68 of the synchronizer, thence to binding-post 119, 105 then to binding-post 120, from which it is carried through the restoring-magnet 39 of the minute-release to binding-post 121, and thence to the plus pole of battery B, and then to the minus pole of battery A. It will be observed 110 that when the path of the circuit is as just described the magnets 93, which control the switch 105 and the battery B, are cut out of the circuit. The circuit used during the second period of the hour to send out impulses 115 of normal intensity in the reverse direction of that just described is illustrated in Fig. 8. Starting from the plus pole of battery B the current passes to binding-post 121, then through the magnet 39 of the minute-release 120 to the binding-post 120, thence to binding-post 119, which is connected to magnet 76 and the synchronizer, which magnet controls liquid-switch 68. From the magnet 76 the

current passes from the binding-post 118, thence to binding-post 117, and then through the coil on one leg of the magnet 34 of the repeating-switch 29, thence to binding-posts 5 116, then to binding-post 115, from which it passes to terminal *d* of the liquid-switch 105, thence through the conducting liquid of said switch to terminal *e*, to binding-post 114, thence to binding-post 113, then to terminal 10 32 of the liquid-switch 30 of the repeating-switch, through the conducting liquid to the terminal 31, thence to binding-post 112, then through the other leg of the magnet 34, thence to the binding-post 111, then to binding-post 15 110, from which it passes through the secondary-clock circuit and enters the master-clock at binding-post 109, thence to binding-post 108, to the terminal *b* of the liquid-switch 68, through the liquid of said switch 20 to the terminal *c*, thence to binding-post 122, then to the minus pole of battery *b*. In this case the circuit is the same as that described during the first period, except that the impulses are sent out in the reverse direction 25 from those of the first period, and battery *A* and magnets 93, which restore the switch 105, are inoperative. During the third period of the hour, which is very short relative to the two periods just described, impulses of greater 30 intensity are sent out in quick succession and in the same direction as those sent out during the second period of the hour. Starting at the plus pole of battery *A*, the current passes through binding-post 107 to binding-post 123, 35 thence to the magnets 93, thence to binding-post 124, thence to binding-post 125, thence to the terminal *f* of the switch 105, as shown in dotted lines, thence through the liquid of said switch to terminal *e*, thence to binding-post 40 114, thence to binding-post 113, thence to terminal 32 of liquid-switch 30 of the repeating-switch 29, through the liquid-switch to terminal 31, thence to binding-post 112, from which it is carried to one leg of the magnet 34, then to 45 binding-post 111, thence to binding-post 110, from which point it goes through the secondary-clock circuit and again enters the master-clock at binding-post 109, thence to binding-post 108, then to terminal *b* of the liquid-switch 50 68 of the synchronizer, through the liquid to terminal *c*, thence to binding-post 122, the minus pole of battery *B*, through the minus pole to the plus pole of battery *B*, and then to the minus pole of battery *A*. In this 55 case the impulses are of double the intensity of those sent out during the first two periods of the hour, as both batteries *A* and *B* are connected. During this period the following portions of the circuit employed during the 60 first two periods are cut out: magnet 76, which controls the switch 68 of the synchronizer, magnet 39 of the restorer for the minute-release, and one leg of the magnet 34, which operates the repeating-switch 29. 65 I will now describe the operation of the synchronizer which I employ, which performs two very important functions, viz: changing the

direction of the impulses which are sent out by the master-clock during the first two periods of the hour and the sending out of impulses of double intensity and in quick succession during the third period of the hour. It will be noted that the synchronizer does not in itself make and break the circuit; but the switches 68 and 105 when changed from their normal position by the mechanism which I am about to describe alter the path of the current when the circuit is closed by the repeating-switch in the manner already described. As illustrated in the drawings, Figs. 1 and 2, the position of the high and low parts of the cam 41 determines the position of the switches, and consequently the kind of current which will be sent out by the master-clock. When the parts are in the position shown in Fig. 1, the pin 48 being on the low part 42 of the cam 41, the lever 45 is held in such a position that the pin 50 on the arm 49 of said lever engages the pin 52 on the bell-crank lever 54, and thus prevents the lever 54 from falling. The weighted arm 56 of this lever is connected by a link 57 to a tripping-lever 58, having an adjustable pin 58', which in the positions shown in Figs. 1, 3, and 4 is held out of contact with the arm 63', which 80 operates the switch-holding catch 64, and the arm 82, which acts as a detent to the arm 83, which is on the axis of the switch 105. When the cam rotates during the first period of the hour and the parts are in the position just described, the repeating-switch is released once a minute, and since the detent 26 is restored by the magnet 39 in the manner previously described but a single impulse is sent out for each revolution of the seconds-hand cam 4. 85 When the incline 41', leading to the high part of the cam 41, reaches the pin 48, the arm 47 is depressed, as shown in Fig. 2, and the pin 50 on the weighted arm 49 of lever 45 is raised so that the pin 52 on the arm 53 of bell-crank lever 54 is released and falls until it engages the pin 51 on the arm 49. This movement, by means of the link 57, connected to the tripping-lever 58, depresses said lever so that the adjustable stop 58' comes in 90 contact with the arm 63' on the shaft 63 and depresses it, thereby moving the catch 64 so as to unlock the arm 66 upon the shaft 67, which forms the axis of the liquid-switch 68, thus allowing the counterweight 67' to tip 95 the switch 68 into the position shown in Fig. 8. This release of the switch 68 occurs between two consecutive impulses, so that after the switch 68 has been tipped downwardly by the counterweight the next impulse will be sent out by the master-clock through the new path made by the switch 68, as described in the circuit of the second period—namely, in the reverse direction to that of the first period. The catch 65, which is operated at the same time that the catch 64 releases the switch 68, moves into the path of the pin 71' on the arm 71, which is secured 100 to the shaft 74, which carries the armature 105 110 115 120 125 130 135

75 of the magnet 76, by which the switch 68 is restored to normal position, as I shall hereinafter describe. During this period the impulses are sent out once a minute, but in the 5 reverse direction, by the repeating-switch. As the cam 41 continuously revolves the pin 48 drops from the high part 43 of the cam to the low part 42, and in so doing the weighted arm 49 of the lever 45 drops, thus releasing 10 the arm 53, which falls still further under the action of the weighted arm 56, and by its connection to the tripping-arm 58 and the adjustable pin 58' still further depresses the arm 63' on the shaft 63 and causes said arm 15 to engage the tail of the detent 82 on the shaft 81, thus tipping said detent into the position shown in full lines in Fig. 6. This movement of the detent releases the arm 83, which holds the switch 105 against the action 20 of its counterweight 106 and allows the switch to tip under the action of the counterweight so as to establish a new path for the current, as shown in dotted lines in Fig. 8. This change of the switch also occurs between two 25 consecutive impulses sent out by the repeating-switch, and when the switch 105 is thus tipped currents or impulses of double the intensity of those previously sent out and in the same direction of those of the next preceding period are sent out the next time 30 the repeating-switch is tripped by the seconds-hand cam, since the restorer-magnets 39 are cut out of the circuit, thus preventing the detent 26 from engaging the toothed 35 segment 27 of the repeating-switch, and so long as the switch 105 remains in the tipped position the repeating-switch will continue to send out impulses of double intensity and in quick succession until the switch 105 40 is again restored to its normal position, as shown in full lines in Fig. 8. This restoration is accomplished in the following manner: Before the tube 105 is restored to its normal position the magnets 93, which are now in 45 circuit, cause the armature 92 to vibrate for each current sent out by the repeating-switch, and with each vibration the toothed wheel 96 will be fed by the pawl 95 one tooth by the vibration of the armature. The disk 100, 50 which is mounted upon the shaft 99, to which the toothed wheel 96 is also secured, is provided on its face with notches which are somewhat similar to the locking-plate of an ordinary striking-clock. If the finger 104, mounted upon shaft 102, be in the position shown 55 in Fig. 3 and the tubes and the switches 68 and 105 be in the position shown in dotted and full lines in Fig. 8, the first feeding stroke of the magnets 93 will turn the disk 60 100, so that the finger 104 will be lifted out of the notch and rest upon the periphery of the disk. This movement brings the arm 103 into the full-line position shown in Fig. 6. By means of pin 103' the weighted end of 65 pawl 86 is lifted, thus depressing the forward extension of the pawl, so that upon the next back stroke of the armature the switch 105

will not be returned to its normal position. On the first forward stroke of the armature 92 the releasing mechanism of the synchronizer, through the link connection previously described, restores this portion of the mechanism into its normal position, without, however, accomplishing the resetting of the switches 68 and 105. In the case just supposed the disk 100 will permit the armature 92 to make three strokes before resetting the switch 105, for the reason that the magnets 39 of the restorer of the minute-release are cut out of the circuit and the detent 26 of 75 the repeating-switch is held out of engagement with the toothed segment 27, and said switch will be permitted to vibrate as long as the detent is held out of engagement. The third period is ended by the restoration of 80 the switch 105 to its normal position upon the back stroke next succeeding the three forward feeding strokes in the case just described. As soon as the switch 105 is restored to its normal position by the back stroke of 85 the armature 92 an impulse is sent out, since the repeating-switch has not yet stopped. Said impulse will pass through the same path as that of the second period of the hour, and the restoring-magnet 39 being again in circuit the arm 36, controlled thereby, will lift 90 the releasing mechanism of the minute-release, and thereby restore the detent 26 to a position to engage the toothed segment 27, and thus stop the repeating-switch from sending out any more impulses. During this last 95 impulse sent out by the repeating-switch the magnets 76, which control the armature 75, which acts to restore the switch 68 to its normal position, accomplishes this movement 100 upon the back stroke of the armature, since the arm 71, actuated by the armature 75, is free to move because of the fact that the catch 65 has been restored to its normal position out of the path of the pin 71' on the first 105 stroke of the armature 92 of the third period of the hour, and the first movement of the armature 75 during the sending out of the impulse immediately succeeding the third 110 period of the hour is drawn into the position 115 shown in dotted lines in Fig. 4, and the pawl 70, mounted thereon, being freed from the stop-pin 73 and actuated by the spring 70', will be brought into the position shown in 120 dotted lines, so that its end will engage the finger 69 upon the shaft 67, which is the axis of the switch 68, upon the next back stroke of the armature 75, thereby restoring the switch to its normal position, where it is again held by the catch 64, which engages the arm 125 66 upon its axis 67. This completes the cycle of operation.

It will be obvious from the foregoing description that during the first thirty minutes of the hour, the cycle starting at the first minute 130 of the hour, impulses of normal intensity will be sent out once a minute in one direction, this constituting the first period of the hour. Then the switch 68 of the synchronizer being

dropped will establish a path for the current, so that the repeating-switch will send out impulses once a minute for the remainder of the hour and with the same intensity as those 5 of the first period, but in the opposite direction, until the end of the fifty-ninth minute of the hour, at which time the switch 105 is dropped, and upon the next succeeding release of the repeating-switch by the seconds- 10 hand cam impulses of double intensity, but in the same direction as those in period two, will be sent out by the repeating-switch. The number of these currents depends upon the condition of the disk 100 and will vary from 15 one to twelve in the clock arranged as shown. On the last back stroke of the armature 92 the switch 105 is restored. This constitutes the third period of the hour, and during this 20 period the secondary clocks which are slow are set up and if provided with striking mechanism will strike the hour to correspond to the number of currents sent out during this period. A restoring-current which belongs neither to the first, second, or third 25 periods, but which goes over the same path as the second period of the hour and of a duration of but a single impulse, is sent out immediately after the conclusion of the third period and before the beginning of the first. 30 This impulse restores the switch 68 to its normal position and establishes a normal path for the first impulse of the new hour. This completes the cycle of the impulses sent out during the hour.

35 The type of secondary clock which I employ is diagrammatically shown in Fig. 7 and is provided with an electrical driving mechanism 126 of any suitable construction. A toothed wheel 127, with sixty teeth thereon, 40 is secured to the arbor which carries the minute-hand, and this wheel is provided with pin 128, which is adapted to be engaged by a polarized detent 129, which is held in a position not to engage the pin during the first 45 period of the hour, but which will be pulled over into the position to engage the pin (shown by dotted lines in Fig. 8) during the second and third periods of the hour, since the impulses of these periods are sent out in 50 the reverse direction from those of the first period, and any slow clocks will be advanced toward twelve one minute for each impulse of the third period of the hour. The clocks which are correct will have the detent in engagement with the pins on the minute-hand wheel, and the detent will prevent these 55 clocks from being affected by these impulses. Upon the first impulse of the first period of the new hour the detents 128 will be thrown out of engagement and the minute-hand of the secondary clock will be advanced one minute at a time at each impulse sent out by the repeating-switch during the first two 60 periods of the hour. As shown in Fig. 7, I have provided the secondary clock with a single-stroke electric bell and on the same circuit as the secondary clock. This magnet

may be in series or in parallel with the main actuating-magnet of the secondary clock, as best suits the particular case where these 70 clocks are employed. This bell is so adjusted that it is not affected by the currents of normal intensity sent out by the repeating-switch of the master-clock during periods one and two, but is actuated by the currents 75 of double intensity of the third period.

From the foregoing description it will be apparent that the secondary clocks are each hour brought into synchronism with the master-clock. The exact time is determined by 80 the position of the cam 41 on the minute-hand of the master-clock, and the high and low parts of this cam determine when these three periods shall begin. It is obvious that by altering the position of the cam 41—that is, by turning 85 it forward or back—the secondary clocks will be brought into synchronism with it at the beginning of the next succeeding third period, so that all that is necessary in order to set the secondary clocks on the circuit forward or back is to turn the cam 41 on the minute-hand arbor of the master-clock the desired number of minutes, when upon the next following third period the secondary 90 clocks will be brought into synchronism with 95 the master-clock. This change of position may be made by hand or may be accomplished by any suitable means for synchronizing self-driven clocks, one form of which is shown in dotted lines in Fig. 1, in which a circuit-closer 100 130 closes the circuit through the magnet 131, which actuates the armature 132, attached to a lever 133, provided with two branches 134 and 135, provided with suitable rollers at their ends adapted to engage the cams 5 and 44 on the seconds-hand arbor and minute-hand arbor, respectively, so that when magnet 131 is energized the seconds-hand is brought to 105 60 and the minute-hand is brought to some predetermined point by the clock which controls the circuit-closer 130. As this method is well known in the art, further description 110 of this part of the system is unnecessary.

In Figs. 9, 10, and 11 I illustrate the preferred form of my secondary clock in more 115 detailed views. As shown in these figures, the electrical driving mechanism consists of an electromagnet 136, having its armature 137 pivoted on a lever 138, having a counter-weighted arm 139. The lever 138 is pivoted 120 at 140, and the upper arm of this lever carries a pivoted pawl 141, engaging the teeth of the main wheel 127. A retaining-detent 142 also engages the teeth of wheel 127, this preventing backward rotation of the wheel 125 when the pawl 141 is moved back to engage the next tooth. The polarized detent 129 is pivoted to a brass strip 143, secured to the front and shorter leg of a permanent horseshoe magnet 144. The detent swings between 130 pole-pieces 145, secured to the opposite poles of an electromagnet 146, and the hooked end of the detent is in position to engage the pin 128 when the parts are in the position shown

in Fig. 9, this being the position during the second half-hour. The operation of these parts is as set forth in the previous description of the secondary clock. The electric driving mechanism, consisting of the magnet and counterweighted armature-lever, moves the wheel 127 through the pawl 141 and through the connected gearing of usual form the hands of the clock are actuated.

10 The advantages of my synchronizing system are many, since by its use I am enabled to employ secondary clocks of the step-by-step type which are synchronized every hour automatically by a master-clock which sends out impulses to accomplish this result. The master-clock which I employ is so constructed as to drive the secondary clocks, synchronize them, and when provided with a single-stroke electric bell I am enabled to strike the 20 hour on the secondary clock without the addition of extra mechanism to the secondary clock, also to set them up, and I am enabled to accomplish all these results with a single circuit. The synchronizing of secondary 25 clocks of the step-by-step type when automatically controlled by a master-clock, such as shown, renders these secondary clocks reliable, since it is at once apparent whether the clock is operating properly, because of the fact that the clock is either stopped 30 because of some derangement or broken connection with the master-clock. If properly connected, the secondary clock operates in the usual manner and is sure to be correct, 35 since it is synchronized automatically once each hour by the master-clock. By providing the secondary clocks with a circuit which is made and broken only by the master-clock and then synchronizing the clocks over this 40 circuit it is impossible for the secondary clocks to fail because of imperfect contacts in them, which have heretofore been employed. Another advantage is that by employing the master-clock of the type shown, 45 in which the synchronizer which controls the secondary clock is controlled by a cam rigid with the minute-hand, the setting of this cam or minute-hand forward or back will at the next synchronizing period set the secondary 50 clocks forward or back the same amount, and this movement of the cam may be accomplished either by hand or by connecting the synchronizing circuit-breaker 130 with an observatory-signal. Hence a signal sent from 55 the observatory will first synchronize the master-clock, and then the master-clock at its next ensuing synchronizing period will synchronize the secondary clocks on the circuit. So far as I am aware this has never 60 been accomplished heretofore, nor has it been possible heretofore to automatically synchronize secondary clocks of the step-by-step type on a single circuit. While I have described the extra impulses by which the secondary 65 clocks are set up as being of double intensity, it is obvious that this need not be

so, as impulses of normal intensity will serve equally well and accomplish this purpose.

Many changes may be made in the form and arrangement of the parts by those skilled in the art, since

What I claim is—

1. In a synchronized clock system, a series of secondary clocks, a master-clock having connections arranged to give electric impulses to them at determined intervals and for a determined period in one direction, and mechanism for sending out impulses for another period at determined intervals in the opposite direction; substantially as described. 70

2. In a synchronized clock system, a series of secondary clocks, a master-clock having connections arranged to give electric impulses to them at determined intervals in one direction, and for a predetermined period, and in 85 the opposite direction at determined intervals and for a predetermined period, followed by a series of impulses in quick succession and in the same direction as the last preceding period, whereby the secondary clocks are 90 synchronized; substantially as described.

3. In a synchronized clock system, a master-clock having connection with a series of secondary clocks arranged to give electric impulses to them at determined intervals in one 95 direction and for a predetermined period, and in the opposite direction at determined intervals and for a predetermined period, followed by a series of impulses of augmented intensity 100 in quick succession and in the same direction as the last preceding period, whereby the secondary clocks are synchronized; substantially as described.

4. In an electric clock, a switch normally locked, releasing mechanism adapted to unlock said switch so as to make and break the circuit at predetermined intervals; mechanism adapted to restore the releasing mechanism to its normal position, in which said switch is locked, said restoring mechanism being in 110 the same circuit with said switch; substantially as described. 105

5. In an electric clock, a switch adapted to send out impulses at predetermined periods, releasing mechanism operated by the clock-movement adapted to unlock said switch at said predetermined interval, secondary clocks adapted to receive impulses sent out by said switch, mechanism adapted to restore the releasing mechanism to its normal position, in 115 which said switch is locked and the circuit is broken, said restoring mechanism being in the same circuit with said switch and secondary clocks; substantially as described. 120

6. In an electric clock having a switch adapted to send out impulses at predetermined intervals, a synchronizer having switches adapted to change the direction of the impulses sent out by said switch; substantially as described. 125

7. In an electric clock having a switch adapted to send out impulses at predetermined in-

tervals, a synchronizer having switches adapted to change the direction and intensity of the impulses sent out by said switch; substantially as described.

5 8. An electric clock having a switch adapted to send out impulses at predetermined intervals, a synchronizer having switches adapted to change the direction of said impulses, a cam operated by the clock mechanism and arranged to control the switches of the synchronizer, thereby determining the period during which impulses are sent out in a given direction; substantially as described.

9. In an electric clock having a switch adapted to send out impulses at predetermined intervals for predetermined periods and in quick succession for another period relatively short, releasing mechanism controlling said switch, a restorer normally adapted to reset said releasing mechanism and lock said switch after each impulse during the longer periods, a synchronizer having switches adapted to change the direction of the current during the long periods, said restorer being normally in circuit with the switch which sends out impulses at predetermined intervals, but adapted to be cut out of said circuit by one of the switches of the synchronizer during the relatively short period during which said switch which sends out impulses, so that said switch is permitted to send out a series of impulses in quick succession; substantially as described.

10. In an electric clock having a switch adapted to send out impulses at predetermined intervals, a synchronizer having switches adapted to change the direction of the impulses sent out by said switch, releasing mechanism operated by the clock mechanism by which the interval at which said impulses are sent out is determined, a synchronizer having switches adapted to change the direction of said impulses, a cam operated by the clock mechanism arranged to control the switches of the synchronizer, thereby determining the period during which impulses are sent out in a given direction; substantially as described.

11. In an electric clock provided with a switch adapted to send out impulses, a synchronizer having switches arranged to form a portion of a path for said impulses, said synchronizing switches being adapted to change the direction in which said impulses are sent out; electromagnets forming a part of the circuit and adapted to effect the restoration of said switches to their normal position on the back stroke of their armatures; substantially as described.

12. In an electric clock having a switch adapted to send out impulses at predetermined intervals, a synchronizer having switches released in succession, mechanism operated by the clock mechanism by which said release is effected, said switches when released altering the direction in which the impulses are sent out, electromagnets located in circuit with said switches adapted to re-

store them to their normal position in the reverse order to which they were released upon the back stroke of the armatures; substantially as described.

13. In an electric clock having a switch adapted to send out impulses at predetermined intervals, a synchronizer having switches released in succession, mechanism operated by the clock mechanism by which said release is effected, said switches when released altering the direction in which the impulses are sent out, electromagnets located in circuit with said switches adapted to restore them to their normal position upon the back stroke of the armatures; substantially as described.

14. In an electric clock having a switch adapted to send out impulses at predetermined intervals released by the clock mechanism, a synchronizer having a switch also released by said clock mechanism, said switch being adapted when released to change the direction without altering the interval at which said impulses are sent out; substantially as described.

15. In an electric clock having a switch adapted to send out impulses at predetermined intervals released by the clock mechanism, a synchronizer having a switch also released by said clock mechanism, said switch being adapted when released to change the direction without altering the interval at which said impulses are sent out, and a second switch adapted to be released by said clock mechanism after the first switch has been released, whereby the frequency of the impulses sent out is permitted until said switch is returned to its normal position; substantially as described.

16. In an electric clock having a switch adapted to send out impulses at predetermined intervals released by the clock mechanism, a synchronizer having a switch also released by said clock mechanism, said switch being adapted when released to change the direction without altering the interval at which said impulses are sent out, a second switch adapted to be released by said clock mechanism after the first switch has been released, whereby the frequency of the impulses sent out is permitted, and a locking-disk provided with a series of notches arranged at intervals, an electromagnet in circuit with the impulse-sending switch and said second switch of the synchronizer, feeding mechanism actuated by said electromagnets, whereby said locking-disk is fed step by step, resetting mechanism for said second switch which is held out of operative position during the interval between the notches in said locking-disk, said switch being returned to its normal position when the resetting mechanism again engages the next succeeding notch in the locking-disk; substantially as described.

17. In an electric master-clock having a switch adapted to send out impulses at predetermined intervals, a releasing mechanism

therefor, a restorer for said switch in circuit therewith, a synchronizer having switches adapted to change the direction and intensity of said impulses, electromagnets having vibrating armatures adapted to restore said switch, resetting mechanism secured to said armatures, clock mechanism adapted to determine the time at which said change of direction and intensity takes place, releasing mechanism operated by said clock mechanism by which said synchronizer-switches are released in succession, one of said switches altering the direction of the impulses sent out without affecting the intensity of the current, the second switch of said synchronizer being adapted to increase the intensity of the current without changing its direction, said second switch permitting the repeating-switch to send out impulses of augmented intensity in rapid succession, feeding mechanism actuated by the vibrating armature of one of said electromagnets, releasing mechanism whereby said synchronizing-switches are operated, also actuated thereby, said armature resetting said releasing mechanism for both switches on its first feeding stroke, a locking-disk adapted to be actuated by said feeding mechanism, notches in the periphery of said locking-disk arranged at intervals, resetting mechanism for said second switch adapted to engage the notches and the periphery of said locking-disk, the space between said notches determining the number of impulses of augmented intensity sent out by the repeating-switch in quick succession, said second switch with the

synchronizer being restored to its normal position on the first back stroke of the electromagnet which operates the locking-disk when the resetting mechanism is dropped into registry with the next succeeding notch, the resetting of said switch again completing the circuit through the restorer for the repeating-switch, and thereby establishing the circuit through the magnet of the synchronizer-switch first released, and thereby actuating its armature and the resetting mechanism secured thereto so that upon the back stroke of the armature, the first-released switch of the synchronizer is returned to its normal position; substantially as described.

18. A synchronized clock system comprising a primary clock having connection with a self-driven master-clock, mechanism by which said master-clock is synchronized therewith, said master-clock having connections with a series of secondary clocks arranged to give electric impulses to them at determined intervals and for determined periods in one direction, and mechanism for sending out impulses for another period and a determined interval in the opposite direction, whereby said secondary clocks are synchronized with said master and primary clock; substantially as described.

In testimony whereof I have hereunto set my hand.

ARTHUR F. POOLE.
